UNITED STATES PATENT OFFICE.

FERDINAND UNCKRICH, OF GALION, OHIO.

VAULT-CLOSURE.

No. 872,864.

Specification of Letters Patent.

Patented Dec. 3, 1907.

Application filed April 18, 1907. Serial No. 368,912.

To all whom it may concern:

Be it known that I, FERDINAND UNCKRICH, a citizen of the United States, and a resident of Galion, in the county of Crawford 5 and State of Ohio, have invented a new and Improved Vault-Closure, of which the following is a full, clear, and exact description.

This invention relates to vault closures, and is particularly useful in connection with 10 devices of this class intended for locking and hermetically sealing grave vaults.

The object of the invention is to provide a simple, strong and durable vault closure by means of which the vault opening can be 15 securely locked from the outside and which effects a hermetical sealing of the vault opening.

A further object of the invention is to provide a vault closure which when locked in 20 position, closing the vault opening, cannot be re-opened without destroying the closure.

The invention consists in the construction and combination of parts to be more particularly described hereinafter and fully set 25 forth in the claims.

Reference is to be had to the accompanying drawings forming a part of this specification, in which similar characters of reference indicate corresponding parts in all the views, 30 and in which

Figure 1 is an elevation of the inner face of my vault closure showing the locking mechanism in an operative position; Fig. 2 is a similar view of a part of the invention showing 35 the locking mechanism in an inoperative position; Fig. 3 is a vertical section on the line 3—3 of, Fig. 2, showing the closure locked in position upon the vault opening; Fig. 4 is a similar view showing the locking 40 mechanism in position, hermetically to seal the vault opening; and Fig. 5 is an elevation of a detail.

Before proceeding to a more detailed explanation of my invention it should be understood that it is desirable in many cases to provide grave vaults and the like with strong, durable and hermetically sealed closures for the openings thereof to prevent unauthorized admission to the vaults and to 50 insure the preservation of the contents of the same. I provide a vault closure comprising a door-plate adapted to seat against a door-frame; the plate and the frame are preferably of steel, iron or the like.

55 The door-frame may be secured at the vault opening by means of bolts or rivets, or

in any other suitable manner, depending upon the construction of the vault, which may be of metal, stone-work or the like. Slidably mounted upon the inner side of the door-plate are bolt members which can be projected toward the edges of the door behind the lateral flanges of the door-frame, thereby locking the door in position against the frame. The bolt members are projected by means of a rotatable cam having lobes 60 engaging with the bolt-members to thrust them outwardly toward the edge of the door-plate when the cam is rotated. A key-bolt member is arranged near the center of the door-plate and has a threaded part located in a suitable threaded opening in the cam member. The key-bolt presents a square head at the outer face of the head by means of which the operating mechanism may be 65 actuated through the aid of a suitable wrench or spanner. A frangible member comprising preferably a soft metal plug serves to secure the cam member to the key member, so that when the latter is rotated the cam is 70 similarly actuated to project the bolts.

When the bolts are projected to the limit of their movement the rotation of the cam member is resisted, whereupon the frangible member is broken. When this takes place 75 the key bolt member is free to turn in the threaded opening in the cam member, whereupon the cam is forced outwardly from the face of the door-plate and carries with it by means of a projecting shoulder the 80 bolt members. By thus forcing the bolt members outwardly the door-plate is clamped against the door-frame to effect the hermetical sealing of the vault openings.

Referring more particularly to the drawings, 1 represents a vault having an opening with the door-frame 3 arranged therein. The door-frame 3 has an inwardly disposed flange 4 and is secured in place by means of screws or rivets 5. Seating against the door-frame is a door-plate 6 having a projection 7 adjacent to the edge and presenting a curved surface 8. The projection 7 extends all the way around the door-plate. The outer face of the door-plate may be 90 provided with the usual central boss 9 and strengthening ribs 10. A key-member 11 is carried by the door-plate and has a squared head 12 projecting beyond the outer face thereof. The key-member 11 has a threaded part 13 extending beyond the 95 inner face of the door-plate, and it is further

provided with an annular shoulder 14 normally seating against the inner face of the door. A cam-member 15 is mounted upon the threaded part 13 of the key-member by means of a suitable threaded opening therethrough. The cam-member 15 has cam lobes 16 and a flange 17 normally adjacent to the inner face of the door, provided with teeth 18 and constituting a ratchet-wheel. 10 A dog 19 is carried by the door and engages with the ratchet-wheel to lock the cam against rotation in one direction. The cam-member 15 has a recess 20 adapted to receive the shoulder 14 of the key-member. The 15 recess 20 and the shoulder 14 are provided with lateral recesses in which is located a soft metal plug 21 constituting a frangible member, adapted normally to connect the cam and the key-member and to secure 20 them together.

Bolts 22 are slidably mounted upon the inner face of the door by means of suitable guides and are movably seated on the projection 7 of the door. The bolts are preferably 25 triangular in form and have toes 23 at the sides adjacent to the edges of the door, the apexes of the triangles extending toward the center of the door-plate and presenting rounded edges 24 and shoulders 25. The 30 bolts are cut away near the middle portions to form guide-bars 26 arranged in guides 27 carried by the door. The guides are formed by plates 28 riveted to the door face and having laterally disposed flanges 29. The 35 bolts 22 have slots 30 in which are located projecting lugs 31 carried by the door and integral with the projection 7. Arranged between the door and the end of the slots 30 are helical springs 32 which force the bolts 40 away from the edge of the door towards the center thereof. The lugs 31 have transversely projecting pins 33 adjacent to the outer faces of the bolts, adapted to retain the same in position. The pins 33 are arranged 45 substantially in alinement with the projections 7 and are thus adapted to serve as fulcrums when the bolt members are rocked upon the projections 7 by the movements of the cam member 15 away from the 50 door face.

The operation of my invention is as follows: Before the closure is placed in position upon the opening of the vault, the bolts are drawn into the position shown in Fig. 1, the 55 dog 19 being lifted from engagement with the ratchet 17 if necessary, to rotate the key member in the reverse direction to the locking movement. In the position indicated in Fig. 1 the shoulders of the lobes 16 of the 60 cam rest against the shoulders 25 of the bolts. The door is then placed in position with the edges seating against the flanges of the door-frame. A lead gasket 34 being placed between the door-frame and the edge of the 65 door when the door is in position. The key-

member is rotated by means of a wrench or spanner and the bolts are thereby forced outwardly. The curved lobes 16 engaging the curved edges 24 of the bolts to effect the outward movement of the same against the resistance of the springs 32. When the bolts have been shot home as far as possible the ends of the bolts extend a considerable distance behind the flange 4 of the door-frame, thereby securely locking the door in position 75 upon the door-frame. The key-member is further rotated in the same direction and as the resistance increases the frangible member 21 can no longer withstand the shearing action between the key-member and the 80 cam, and is broken. A further continuous movement of the key-member forces the cam outward from the face of the door-plate owing to the arrangement of the threaded part 13 and the similarly threaded opening in 85 the cam. As the cam is forced away from the door it carries with it by means of the shoulder 17, the inner ends of the bolts, rocking the same upon the projection 7 against the pins 33 as fulcrums; in consequence, the outer extremities of the bolts—the toes 23—are clamped against the flange 4 thereby tightly drawing the door against the door-frame, and in this way effecting a hermetical sealing of the vault opening, the 90 lead gasket 34 being jammed between the door and the door-frame.

A retaining plate 35 is mounted upon the cam 15 by means of a screw 36 and extends laterally over the inner ends of the bolts. 100 The plate 35 serves to hold the inner ends of the bolts in position upon the door.

Having thus described my invention, I claim as new and desire to secure by Letters Patent:—

1. A vault closure, comprising a door adapted to seat against a door-frame, bolts movably mounted on said door, an operating member formed in sections to project said bolts, a frangible member connecting said sections and adapted to be broken when said bolts are forced home, and means for clamping said bolts against said frame by a continuous movement of said operating member. 105

2. A vault closure, comprising a door adapted to seat against a door-frame, bolts carried by said door, and a key-member having an initial movement adapted to project said bolts behind said frame, and having a second movement adapted to clamp said 115 bolts against said frame.

3. A vault closure, comprising a door adapted to seat against a door-frame, slideable bolts, means for successively projecting said bolts towards said frame, and for forcing 120 said bolts into an inclined position with respect to the face of said door to clamp said bolts against said frame.

4. A vault closure, comprising a door adapted to seat against a door-frame, slid- 130

- able bolts carried by said door, a key member mounted upon said door, a cam carried by said key member and adapted to project said bolts when said key member is operated, said 5 key member having means controlled by its movement for clamping said bolts when the latter are projecting against said door-frame.
5. A vault closure, comprising a door adapted to seat against a door-frame, slid- 10 able bolts carried by said door, a key member movably mounted upon said door, a cam carried by said key member and adapted to project said bolts toward the edge of said door, said key member serving to clamp said bolts 15 against said door-frame when said bolts are projected, and means for locking said key member against momentum in one direction.
6. A vault closure, comprising a door adapted to seat against a door-frame, slid- 20 able bolts carried by said door, a rotatable key-member, a cam comprising a lobe adapted to project said bolts, a frangible member connecting said key-member and said cam, said cam having a shoulder engaging said 25 bolts, means carried by said key for forcing said cam away from said door when said frangible member is broken, and means for locking said cam against rotation in one direction.
- 30 7. A vault closure, comprising a door adapted to seat against a door-frame and having guides, slideable bolts carried upon said door in said guides, a rotatable key-member having a threaded part, a cam pro- 35 vided with lobes adapted to project said bolts and having a threaded opening adapted to receive said threaded part, a frangible member connecting said key and said cam, said cam having a shoulder engaging said bolts at 40 the side adjacent to said door, said shoulder
- having teeth and constituting a ratchet, and a dog carried by said door and adapted to engage said ratchet to prevent the rotation of said cam in one direction.
8. A vault closure, comprising a door 45 adapted to seat against a door-frame, guides secured to said door, bolts slidably mounted in said guides and having slots in their outer ends, said door having lugs arranged to extend through the respective slots in said bolts 50 for guiding said bolts, means for projecting said bolts and for clamping the same against said frame, and a spring in said slot tending normally to force said bolts toward said operating member. 55
9. A vault closure, comprising a door adapted to seat against a door-frame and having a rounded projection, guides secured to said door, bolts seating on said projection and slidably mounted in said guides, said 60 bolts having slots at the outer ends thereof, said projection having lugs integral therewith and arranged to extend through the respective slots in said bolts, said lugs having projections adjacent to said bolts to hold the 65 same in position, means for projecting said bolts and for clamping the same against said frame, said projections of said lugs constituting fulcrums, and springs in said slots between said lugs and the ends of said slots and 70 tending normally to force said bolts toward said operating member.

In testimony whereof I have signed my name to this specification in the presence of two subscribing witnesses.

FERDINAND UNCKRICH.
